METHOD OF STAPLING BOWS TO
GREETING CARDS

Elaine H. Marshall, Wrentham, Mass.

Application June 9, 1948, Serial No. 31,863

3 Claims. (Cl. 41-34)

1

This invention pertains to a method of making greeting cards and to a card made in accordance with said method.

Greeting cards, for example, birthday cards, Easter cards and so forth are decorated in various ways, one common decorative feature being a ribbon knot or bow. The better grades of card (and these are the ones most frequently decorated with ribbon) are usually of fine, thin paper or at least use such paper for the front member or fold of the card. The paper is selected for artistic appearance rather than strength and is easily torn; and some of these decorative papers have a soft, unglazed surface.

Since the cards must be made to sell within a limited price range the various operations involved in producing them must be as inexpensive as possible commensurate with the artistic appearance demanded. In the interests of low production costs it has been customary to attach the ribbon knot or bow solely by the use of adhesive.

However, the adhesive must be confined to a very small area, that is to say, to the knot itself since the loop and the end portions of the ribbon must be left loose for aesthetic reasons. Thus, even though a powerful adhesive be employed, the small area of adhesion is insufficient to anchor the ribbon so securely to the card as to insure the retention of the ribbon when the card is subjected to the rough and careless handling which it may meet on the display stand, for though the adhesive hold, the soft surface of the paper may be pulled away, thus freeing the knot.

To provide a more certain anchorage it has been proposed to form holes in the front member of the card and to thread the ribbon through these holes and then to tie the ribbon to form the desired knot.

When the ribbon is tied before application to the card (as when it is to be adhesively attached) it is possible to use the ribbon economically and without substantial waste, each knot being tied before the ribbon is severed from the supply and then cut off. However, when the ribbon is to be tied after being threaded through the holes in the card it is almost impossible to gauge the measured length of ribbon accurately, the tying of the knot when the ribbon is already threaded through the card being an awkward and troublesome operation. Thus in following this latter method there is a great waste of ribbon. Moreover, the threading of the ribbon through the holes in the card and the subsequent tying of the knot is a slow and expensive operation.

The principal object of the present invention

2

is to provide a novel method of attaching ribbon knots or bows to greeting cards so that the ribbon will be securely but inexpensively anchored in place, and to a novel card resultant from the practice of this method. A further object is to provide a method whereby the advantages inherent in the use of a pretied knot are availed of but whereby the knot is firmly and adequately united to the card. A further object is to provide a method whereby a pretied knot may be adequately secured to the card without in any way detracting from the appearance of or injuring the external finish of the ribbon and by means which is substantially invisible. A further object is to provide a method of attaching a preformed knot to a card in such a way that even though the material of the card be soft and lacking in strength the knot will not easily tear away. A further object is to provide a card having a ribbon knot attached by card-penetrating fastening means which engages that portion of the knot which contacts the card but which does not penetrate the front or exposed bight of the knot. Other and further objects and advantages of the invention will be pointed out in the following more detailed description and by reference to the accompanying drawings wherein

Fig. 1 is a front elevation of a greeting card of a conventional type decorated with a ribbon knot according to the present invention;

Fig. 2 is a perspective view, partly broken away, showing the card opened to exhibit the interior;

Fig. 3 is a section on the line 3-3 of Fig. 1, the dimensions of the parts being exaggerated for purposes of illustration;

Fig. 4 is a fragmentary, diagrammatic bottom view of a staple-clenching anvil of a type useful in the practice of the method herein disclosed;

Fig. 5 is a section generally similar to that of Fig. 3 but showing the anvil operating in relation to the knot, that is, in the position which it occupies during the clenching of the staple;

Fig. 6 is a front elevation illustrating a decorative knot of another type; and

Fig. 7 is a perspective view of a staple of a type which is useful in the practice of the present invention, the thickness of the wire being exaggerated for illustration.

Referring to the drawings, the numeral 1 designates the greeting card of the present invention. This card, as customary, consists of a piece of thin cardboard, paper or the like and comprises the front member 2 and the rear member 3. The exterior face of the front member 2 carries a

suitable decoration, here indicated diagrammatically by the numeral 4. The sheet of material used in forming the card is usually first folded along a horizontal line as indicated at line 5 (Fig. 2) and then along the vertical line 6. Thus the completed card comprises the aforesaid front and rear members 2 and 3 respectively, and the lining members 2^a and 3^a. Oftentimes an additional ply or plies of material are employed, but whenever the "front member" is herein referred to, it is intended to denote that element of the card which carries the decorative elements which are exposed at the front of the folded card. When, as illustrated in Fig. 2, lining elements such as 2^a and 3^a are used, the inner surfaces of the front and rear members of 2 and 3 are normally concealed by these lining elements.

In accordance with the present invention there is provided, in addition to the decorative feature 4, a second decorative feature 7, consisting of a length of ribbon tied to form a knot. As illustrated in Fig. 1, the knot 7 is of the simplest type, comprising the aligned end portions 8 and 9 of the ribbon and a central bight 11 which extends transversely of the length of the ribbon. This transversely extending front bight or ply of the ribbon covers and conceals underlying portions 12 (Fig. 3) of the ribbon, forming the rear part of the knot.

In attaching this knot to the card, there is preferably employed a staple setting machine or appliance (of generally conventional type) comprising an anvil member 13 (Figs. 4 and 5) having a tapering end portion 15 which may easily be slipped between the front bight 11 of the knot and the underlying or rear portions 12 of the knot as illustrated in Fig. 5. The under side of the anvil has oppositely directed, tapering guide grooves 16 designed to receive the ends of the staple legs and to guide them toward each other as they are bent. This anvil 13 is rigidly supported by an arm 14 and for convenience of operation is disposed substantially horizontally. Other conventional parts of the stapling mechanism are not shown.

The ribbon knot is slipped over this anvil 13 so that the bight 11 overlies the anvil as shown in Fig. 5. The front member 2 of the card is then arranged beneath the anvil, the lining member 2^a being temporarily bent away from the front member 2, and then a staple is passed through the part 2 and up through the underlying portion 12 of the knot, the legs of the staples engaging the underside of the anvil 13 and being guided by the grooves 16 in the anvil so that, as the staple is finally driven into place, the ends of the legs are clenched over and into the underlying portion 12 of the knot but without any possibility of entering the forward bight 11 of the knot. The staple is inserted by the usual staple driving means forming a part of the machine or appliance of which the anvil 13 constitutes an essential part. In thus inserting the staple the bight 11 of the knot is not subjected to any pressure so that no matter how delicate or finely finished its surface, the finish will not be marred by the operation of inserting the staple. A staple of a type suitable for the purpose is illustrated (to much enlarged scale) in Fig. 7. Preferably the head member 17 of the staple should be of the order of $\frac{1}{4}$ inch long in order to provide a good anchorage for the knot even though the material of the part 2 be thin and easily torn. Preferably the wire used in making the staple is flattened so that a substantially flat surface is provided for engagement

with the member 2 of the card, thus further helping to avoid tearing out.

Instead of the simple knot 7 of Fig. 1, knots of more complex type may be employed. Thus, for example, as shown in Fig. 6, the knot 7^a comprises a length of ribbon having end portions 8^a and 9^a and the loop portion 10. This knot also has the transverse front bight 11 as above described. Obviously a knot having a plurality of loops or bows may likewise be used.

By proceeding in the manner above described, the operator is able to dispose the knot at the exact desired position on the front face of the card, since during the stapling operation the front face of the card is fully exposed to view. The card may be located exactly as desired with reference to the knot which has first been mounted upon and is supported by the anvil. The procedure of threading the knot over the anvil and of driving the staple requires but very little time, so that the time factor involved in attaching the knot to the card as herein described is of approximately the same order as that necessary in applying a preformed knot by the use of adhesive, and is much less than that required for threading a ribbon through holes in the card and then tying a knot. On the other hand, the attachment of the knot by means of the staple affords substantially as good a retention of the ribbon as is obtained by threading the ribbon through holes in the card; the waste of material incident to threading the ribbon through the card and subsequently tying the knot is avoided, and danger of damage to the card such as sometimes occurs by smearing with adhesive, or by tearing in threading the ribbon through holes is eliminated. Other types of penetrating fastener may be substituted for the staple, within the purview of the invention, providing such fastener is capable of ready and cheap application without damage to the bight 11, and does not easily tear out of the card.

While a desirable mode of procedure and a specific product thereof has herein been described by way of example, it is to be understood that this invention includes any and all modifications which fall within the scope of the appended claims.

I claim:

1. That method of decorating a greeting card by the attachment thereto of a pre-tied ribbon knot which comprises as steps providing a completed ribbon knot of the desired kind, said knot including a rear portion and an exposed front bight which extends transversely of the length of the ribbon, arranging the pre-tied knot at the front side of the card at the desired location with said rear portion of the knot in contact with the card, inserting a staple from the rear side of the card through the substance of the card and so that the legs of the staple penetrate said rear portion of the knot but do not enter said transverse bight, and clenching the legs of the staple without applying pressure to the exposed face of said transverse bight.

2. That method of decorating a greeting card by the attachment thereto of a pre-tied ribbon knot which comprises as steps providing a completed ribbon knot of the desired kind, said knot including a rear portion and an exposed front bight, the latter extending transversely of the length of the ribbon, arranging the knot at the exposed side of that portion of the card to which it is to be affixed and with said rear portion of the knot in contact with the card, separat-

ing the front bight and rear portion of the knot, providing a staple having an elongate head and spaced legs, disposing the staple at the rear side of that portion of the card to which the ribbon is to be affixed and with the ends of the legs of the staple directed toward the knot, projecting the staple legs through the substance of the card and through said rear portion of the knot and turning the end portions of the legs toward each other so that they lie substantially parallel to the plane of the card and between the front bight and rear portion of the knot.

3. A greeting card having in combination therewith a length of ribbon, all of which is located at the front face of the card, the ribbon being arranged to form a knot having substantially aligned free end portions, the knot proper comprising a rear portion which contacts the card and an exposed front bight which extends transversely of the length of the free ends of the ribbon, and a thin wire staple having an elongate

head of a length of the order of $\frac{1}{4}$ inch and spaced legs, the head being at the rear side of the card, the length of the head being transverse to said exposed front bight, and the forward ends of the legs of the staple being clenched over said rear portion of the knot but failing to enter said bight.
